APPARATUS FOR RAISING OR LOWERING A LOAD.

1,379,546

Specification of Letters Patent. Patented May 24, 1921.

Application filed September 4, 1920. Serial No. 408,384.

To all whom it may concern:

Be it known that I, Dr. RUDOLF FÖRSTER, residing at Essen, Germany, a citizen of the German Republic, have invented a certain new and useful Improvement in Apparatus for Raising or Lowering a Load, of which the following is a specification.

This invention refers to an arrangement for raising or lowering a load by means of two simultaneously acting driving mechanisms, which are positively connected to the load and of which one only serves to impart to the load the desired ascending or descending velocity, while the other is formed by an electro-motor which approximately compensates the weight of the load at all speeds. The object of the arrangement is to enable ascending or descending movements of any value and speed to be obtained independently of the weight of the load and without the aid of any starting device, while the condition of movement of the first driving mechanism, which may be conveniently arranged to be worked by hand and which does not have to perform any work of lifting but which has only to overcome frictional and inertia resistances, can be adjusted in the most accurate manner to suit the speed which is to be imparted to the load and which varies with the working requirements.

The invention will be described with reference to the accompanying drawings in which—

25 Figure 1 shows a construction diagrammatically of an arrangement intended for winding up and letting down a hoisting rope according to the present invention, while

40 Fig. 2 shows a vector diagram, which illustrates the relationship which exists between the most important electrical and mechanical values of the arrangement.

Referring to the drawing in Fig. 1 A 45 denotes a drum for winding up a rope B, which rope B carries on its free end a hook 31 from which the load is suspended. The shaft a^1 of the drum A can be rotated by a hand crank a^2 mounted on one end of the 50 shaft, the other end of which shaft a^1 carries a spur wheel a^3 , with which gears a spur wheel c^1 mounted on a countershaft C. A second spur wheel c^2 mounted on the shaft C gears with a spur wheel d^3 , which is coupled to the shaft d^2 of the rotor D¹ of an

alternating current commutator motor D D¹. The ratio of transmission between the shafts a^1 and d^2 is such that the rotor shaft d^2 rotates considerably more rapidly than the crank shaft a^2 and such that a not too great speed of the crank a^2 corresponds to the highest number of revolutions of the rotor shaft d^2 occurring under like conditions.

The current is supplied to the rotor D¹ of the motor D D¹ by means of two brushes 65 d^5 d^6 running on the commutator d^4 from an alternating current main F of constant tension and frequency. Between the main F and the rotor is placed the winding e^1 of a choking coil E, the magnetic resistance of 70 which can be regulated in the well known way (not shown) by varying the gap between the limbs e^2 and e^3 of its iron core. The exciting winding mounted on the rotor D of the motor D D¹ is likewise connected 75 to the alternating current main F across a regulating resistance G.

The choking coil E placed in the rotor circuit of the motor D D¹ like the regulating resistance G placed in the exciting circuit is only for the purpose of stopping the turning moment developed by the motor D D¹, when at a standstill, and the magnitude of which under otherwise similar circumstances depends only, as is well known, on 80 the tensions impressed on the stator and the rotor. By varying the gap between the limbs e^2 and e^3 of the choking coil E on the one hand and by adjustment of the resistance G on the other hand a means is afforded of setting the turning moment of the motor D D¹ in such a ratio with respect to the moment of the load acting on the shaft a^1 of the drum, that the moment of the load 85 is just compensated.

95 After the load has been suspended from the hook 31 and both the choking coil E and the resistance G so adjusted that the moment of the load is just compensated, the load can be raised or lowered by turning the 100 hand crank a^2 . The man manipulating the crank a^2 is therefore able, to impart to the crank a^2 and therefore to the load, any desired ascending or descending speed, as he has only to perform such an amount for 105 the work, that inertia resistances of the load and the other parts moved are overcome and the losses by friction covered. The moment of the load is compensated when the motor is at a standstill by its turning moment and 110

does not concern the man who works the crank α^2 , no matter whether the crank be turned in the direction in which the load is lifted or that in which it is lowered and with what velocity the raising or lowering of the load takes place.

The proof of this will be furnished by reference to Fig. 2 of the accompanying drawings.

- 10 In Fig. 2, H , J denote the vector of the tension of the mains, J K denoting the ohmic and K H the inductive drop in the tension in the exciting circuit of the motor D D^1 . The field J N of the motor, the value 15 of which is a function of the strength of the exciting current and like it is invariable also oscillates in phase with the vector of the ohmic drop in the tension, that is to say, with the exciting current. If the rotor D^1 rotates, a counter-electromotive force is induced in it, which is comparatively equal 20 to its number of revolutions and which has likewise the same phase as the exciting current. According as the direction of rotation 25 of the rotor, the vector of the counter-electromotive force is of similar direction with the vector of the field or of opposite direction thereto. Thus, for example, the vector J M denotes, according to its magnitude and direction, the counter-electromotive force which is set up when the load is raised at a certain speed, and J R the counter-electromotive force which exists during 30 the lowering of the load.
- 35 In one case therefore M H and in the other R H must indicate the vector of the total drop in the tension in the rotor circuit. This drop in the tension M H or R H can be again divided into the ohmic drop 40 M P or R S and the inductive drop P H or S H , when it is considered that the ratio of the ohmic resistance to the inductive resistance, and therefore also the ratio of the corresponding drops in the tension and accordingly the tangent of the angle opposite 45 the vector M P or R S always remains equal to itself.
- Instead of projecting the vector of the ohmic drop in the tension in the rotor circuit M P or R S on to the field vector J N , we may, for the sake of greater clearness 50 (as has been done in Fig. 2) project the vector of the inductive drop in the rotor circuit on to the vector of the inductive drop 55 in the exciting circuit (H K), which is at right angles to the field vector, in order thereby to obtain a measurement for the turning moment developed by the motor. The section H Q accordingly corresponds to

the turning moment developed when the load is raised at the assumed descending velocity when the load is lowered. The section H K represents, measured on the same scale as H Q and H T , with great approximation the turning moment which is effective when the motor is at a standstill and just compensates the load. It follows at once from a comparison of the three sections H Q , H K and H T , that all three 65 turning moments are of almost the same magnitude. The divergences, which as it is are small, will of course be still less for speeds which lie between those assumed.

Furthermore it is obviously possible, without its being necessary to adduce any 75 proof in support thereof, by reducing the ohmic resistance in the exciting circuit relatively to the corresponding inductive resistance, to still further reduce the aforesaid divergences if necessary. Of course instead of the hand crank α^2 , any other driving mechanism, such as a motor driven one for example, might be used without departing from the spirit of the invention. The hand operated driving mechanism however provides the advantage that the ascending or descending movements of the load can be effected with a fine degree of perception which cannot be secured, when using 85 any motor operated arrangement. 90

Claims.

1. In a hoisting mechanism, the combination of means for imparting the desired ascending and descending velocity, and means comprising an electro-motor for approximately compensating for the load at any speed. 95

2. Apparatus such as set forth in claim 1, in which the compensating motor is a shunt wound commutator motor, having an alternating current source of constant tension and frequency and the rotor circuit of which has, in comparison with its ohmic resistance, a high inductive resistance. 100

3. Apparatus such as set forth in claim 2 in which the rotor has in circuit a choke coil having regulatable magnetic resistance. 105

4. Apparatus such as set forth in claim 1, having hand driven means for imparting the desired velocity to the load. 110

The foregoing specification signed at Essen, Germany, this 12th day of June, 1920.

DR. RUDOLF FÖRSTER.
